UNITED STATES PATENT OFFICE.

WILLIAM R. ORMES, OF WALTHAM, MASSACHUSETTS.

INKER FOR TYPEWRITER-RIBBONS.

1,391,139.

Specification of Letters Patent. Patented Sept. 20, 1921.

Application filed December 27, 1920. Serial No. 433,318.

To all whom it may concern:

Be it known that I, WILLIAM R. ORMES, of Waltham, in the county of Middlesex and State of Massachusetts, a citizen of the 5 United States, have invented a new and useful Improvement in Inkers for Typewriter-Ribbons, of which the following is a specification.

My invention is designed to serve as a desk 10 or office appliance for the reinking or re-moistening of typewriter ribbons. The ink on ribbons dries in time and they are often thrown away when in fact the fabric has considerable life provided it can be re- 15 moistened or reinked. Usually under these conditions the ribbon is thrown away, whereas all that is necessary to revive it is to apply to it some proper liquid. Heretofore as far as I know machines useful for reviving 20 ribbons have not been adapted for ordinary office use. They have been quite large and complicated and particularly adapted for use in factories where the ribbon is manufactured.

25 My invention will be understood by reference to the drawings, in which—

Figure 1 is a side elevation of a machine embodying my invention;

Fig. 2 a plan thereof;

30 Fig. 3 an end elevation showing the support for one of the reels;

Figs. 4 and 5 sections on lines 4—4 and 5—5 of Fig. 2; and

35 Fig. 6 a perspective view of the moistening tank.

A is a table which may be of wood or other suitable material on which is mounted a base plate B having projecting upwardly therefrom a rib C. This rib is shaped at 40 each end as shown at D, E, to form bearings for studs d, e on which the reels are mounted, it being understood that the reels herein referred to are reels of ordinary character used in typewriting machines. On the stud 45 d is mounted a crank arm F with a suitable crank handle, bearings F¹ being provided therefor in any suitable manner. The end of the stud d is threaded to receive a nut d² by which a reel is clamped onto the stud 50 against the washer d³ so that it may be rotated by the crank. At the other end of the device the means for holding a reel upon the stud e comprises a rod G mounted to slide lengthwise and free to turn in the rib C and 55 a bearing e¹, its outer end being bent laterally as at g and provided with a perforation

g¹ to fit over the end of the stud e. The other end of the rod G carries a head g². Against this head presses one end of a leaf spring G¹ the other end of which is riveted 60 at G² to the rib C. By pressing the rod G inwardly by means of the head g² and against the force of the spring G¹ the arm g is pushed off from the stud e to enable the reel to be put in place on the stud, and when 65 the head g² is again released the spring G¹ forces it toward the position shown in Fig. 2 so that the perforation g¹ being guided by hand onto the stud e rests against the reel and not only holds the reel in place, but applies friction to it so that it will not run on the stud and render the ribbon slack.

On the rib C is mounted a cradle H for the tank J which contains the moistening liquid. In practice I prefer to make my 70 base plate B of two thicknesses of metal which are riveted or otherwise attached together and are shaped and bent as indicated in Fig. 5 so that the rib C is of double thickness, while the ends or edges of the plate 75 are bent outward to form the bed plate B, the upper edge being bent outward and otherwise suitably shaped to form the cradle H. This cradle has an end piece h and side 80 pieces h¹ so that it may be easily slid into 85 place and removed.

The tank is of rectangular shape, its cover J being slotted as at j¹ so that a wick K may be placed in the tank with its end projecting 90 through the slot to engage the roll L and the 90 tank partially filled with a liquid which shall moisten the wick and so carry moisture to the moistening roll L. This roll is carried in uprights l projecting from the top of the tank, and in order to facilitate the removal 95 and replacing of the roll, as may be desirable when filling the tank, I prefer that these uprights l shall be so made that the roll may be sprung into or out of place. On each side 100 of the roll and on top of the tank I mount 100 guide fingers m preferably curved in cross section as shown and projecting from a base M, so that the whole device may be struck out of a single strip of material which is attached as a unit to the top of the tank.

105 This whole construction facilitates economical manufacture, for with the exception of the studs, rod, crank bearings, etc., it may be die cut from sheet metal at very little expense.

110 In using my device, the rod G is first pressed in so that the arm g is withdrawn

from the stud *e* and on that stud a reel wound with dead ribbon, for example of ordinary typewriter form, is placed. The rod *G* is then released and the arm *g* guided 5 back on the stud *e* so that it presses the reel against the opposing wall of the part *E* of the rib *C*. A portion of the ribbon is then drawn off from the reel *N*, passed under the nearest guide finger *m*, over the roll *L*, under 10 the other finger *m* and onto an empty reel *H*¹ which has been put upon the stud *d*, the nut *d*² being first removed. The nut is then screwed home against the reel *N* so that this reel will turn with the crank, and the free 15 end of the ribbon is then attached thereto. The turning of the crank draws the ribbon over the roll *L* which is kept moist by the wick *K* from which it absorbs either a reviving liquid or fresh ink as the case may be. 20 The reel filled with the moistened ribbon may then be removed and inserted in the typewriter in the usual way where it will be found ready for use if the process has been properly and sufficiently carried out. If 25 thought best the ribbon may be run through the machine more than once.

It will be seen that this device is of great simplicity and may be made at comparatively little expense because its size, shape 30 and preferred method of making are such that its main portion may be stamped out of ordinary sheet metal, and moreover when finished it is of such size, say six or seven inches long, that it takes up but little room 35 in an office, and there is nothing to it to get out of order so that it may be used by an office boy as well as by a typist. The tank fitting into the cradle may be easily removed for refilling or interchangeable tanks may 40 be used, one for example containing a moistening liquid and the other ink, in either case the wick serving to convey the liquid to the roll by which the ribbon is moistened.

Other ways of embodying my invention will occur to those skilled in the art as I do 45 not mean to limit myself to the precise construction shown.

What I claim as my invention is:—

1. A device of the kind described comprising a base having reel supports mounted 50 thereon, a tank support mounted between said reel supports, a tank detachably mounted in said tank support, a roll, a roll mounted on said tank, and guides mounted on said tank one on each side of said roll, one 55 of said reel supports carrying a crank arm and the other having means adapted to apply tension to a reel mounted thereon.

2. In a device of the kind described, a reel support comprising a plate, a stud mounted 60 in said plate, a slideable rod mounted in said plate and having a perforated arm at one end, the perforation of said arm being adapted to slide over said stud and hold a reel against said plate, and a spring arm 65 one end of which is attached to said support and the other adapted to engage said rod whereby said arm will be maintained in frictional contact with said reel.

3. In a device of the kind described, two 70 reel supports having a cradle located between them, a tank detachably located in said cradle, a roll mounted on said tank, guides located one on each side of said roll, and means located in said tank whereby 75 said roll may be moistened.

4. A device of the kind described comprising two reel supports, a crank shaft mounted in one of said supports, a friction-controlled rod mounted in the other support 80 to carry a reel, and a moistening device located between said reel supports and comprising a moistening roll and means for moistening it, and guides to hold a ribbon in contact with said roll.

WILLIAM R. ORMES.
